UNITED STATES PATENT OFFICE

ROBERT J. TOBIN, OF HOLLIS, NEW YORK

DESIGN FOR A COMPOSITION ROOFING OR SIDING STRIP

Application filed June 25, 1931. Serial No. 40,323. Term of patent 14 years.

To all whom it may concern:

Be it known that I, ROBERT J. TOBIN, a citizen of the United States, residing at Hollis, in the county of Queens, Long Island, and State of New York, have invented a new, original, and ornamental Design for a Composition Roofing or Siding Strip, of which the following is a specification, reference being had to the accompanying drawing, forming part thereof.

The drawing represents a plan view of a composition roofing or siding strip embodying my new design.

I claim:

The ornamental design for a composition roofing or siding strip substantially as shown.

ROBERT J. TOBIN.
